UNITED STATES PATENT OFFICE.

DANIEL ARIES MACASKILL, OF BROOKLYN, NEW YORK, ASSIGNOR OF ONE-HALF TO
LAWRENCE CUNNINGHAM, OF BROOKLYN, NEW YORK.

ELEVATOR SAFETY APPLIANCE.

Application filed January 9, 1924. Serial No. 685,227.

To all whom it may concern:

Be it known that I, DANIEL A. MACASKILL, a citizen of the United States of America, and a resident of the city of New York, 5 borough of Brooklyn, in the county of Kings and State of New York, have invented new and Improved Elevator Safety Appliances, of which the following is a description.

My invention is a mechanical device for 10 gripping the safety control cable of an elevator car, to bring the elevator car safety into operation manually controllable and operable from the elevator car.

My invention may be used in association 15 with any type of elevator car safety device with means to grip or clutch the elevator car safety control cable, whereby a pull is exerted upon the elevator car safety control cable to bring the elevator car safety into 20 operation.

The general object of my invention is to provide a manually controlled means operable from an elevator car, for bringing the elevator car safety control cable gripping 25 means into action, independently of the automatic controlled devices, to bring the elevator car safety into operation.

Reference is to be had to the accompanying drawings forming a part of this specification, it being understood that the drawings are merely illustrative of examples of the invention.

Figure 1 is a diagrammatic view of an elevator well and car together with the automatic governor for the safety control cable of the elevator car, and of my manually operable safety device and the controlling circuit thereof;

Figure 2 is an enlarged elevation of an 40 example of my improved safety device showing the same installed in connection with one of the known types of automatically controlled cable gripping means;

Figure 3 is a view similar to Figure 2 but 45 illustrating another installation of my invention in association with one type of an elevator car safety control cable gripping device.

Figure 4 is a plan view of the devices 50 shown in Figure 3, parts being broken away.

In the example of my invention shown in Figures 1 and 2 the letter *a* represents a portion of the frame or well of the elevator; *b*, 55 the elevator car; *c*, the cable controlling the

car safety means, usually referred to in the trade as the "safety"; *d*, the wheel over which said cable runs; *e*, the shaft of said wheel geared as usual to the spindle *f* of a centrifugal governor *g*, the lever or arm *h* of which connects by a depending lift member *i* with the grip *j* for gripping the cable *c* against the fixed member *k*. The invention is shown in association with a type of elevator safety devices in which an endless safety control cable *c* runs about the governor sheave *d* and about a weighted sheave *l* in the elevator well at the bottom. The safety control cable of the type referred to has an auxiliary cable *m* secured to a branch *n* of the usual coupling *o* uniting the ends of the cable *c*. Said cable *m* in practice extends to a drum *p* and serves to operate a dog or other elevator safety clutch device for arresting the elevator car *b*, said devices being known. When the cable *c* is held by the grip *j* under operation of the governor *g*, a pull is exerted on said cable and the pull being communicated to the auxiliary cable *m* throws into action the usual dog or other improved elevator car safety controlled by the drum *p*.

In accordance with my invention I provide a pivoted gripping element 10 here shown as pivoted to upstanding lugs 11 on a fixed frame member 12. The pivot shaft 13 of the grip 10 is here shown as provided with an arm 14 having a counter-balance weight 15. The element 10 is adapted to grip the cable *c* between the said element 16 on frame member 12.

The coil 17 of a solenoid 18 is in an electric circuit 19 having a pushbutton 20 for manually closing the circuit. The core 21 of the solenoid 18 when the circuit is closed and said coil energized is adapted to engage and rock a lever 22 here shown as pivoted on a bracket 23 on solenoid 18. The lever 22 connects by a link 24 with a lever 25 fulcrumed between its ends on a pin 125, which lever has an upstanding end 26 disposed beneath an end of the automatically controlled gripping element *j*. Link 24 has a turnbuckle 124 for adjustment.

With the above described construction when the circuit 19 is closed by the elevator operator or other person in or on the elevator car *b* pressing the pushbutton 20, the solenoid 18 will be energized and cause the

core 21 thereof to rock the lever 22. Said lever 22 lies at one end in close relation to the arm 14 of grip element 10 so that in the raising of the lever 22 by the solenoid the arm 14 and gripping element 10 will be rocked and the weighted arm will carry the gripping element to the dotted line position shown in Figure 2 for effectively gripping the cable *c* against member 16. At the same time the connection of the lever 22 through link 24 with the lever 25 will cause the automatically controlled grip element *j* to also be thrown into action for gripping the cable *c* and thus arresting the descent of the car independently of the action of the automatic centrifugal governor *g*. I thus provide means whereby the elevator operator or other person in or on the elevator car can arrest the descent of the car independently of the action of the governor controlled safety means, through the medium of the pushbutton 20 or equivalent circuit controller with which the car is equipped.

The foregoing describes the installation of my improved safety appliance in situations where the governor and automatic safety appliances are already installed. In Figures 3 and 4 I have illustrated a construction and arrangement of the parts suitable for situations where no governor or governor controlled safety grip is already installed, the assemblage of Figures 3 and 4 showing a single grip, a governor to automatically throw the grip into action, and a manually controlled means for throwing the grip into action. The gripping element 110 coacts with the fixed member 116 on the frame *a* to grip the safety control cable *C*, said cable running over a sheave *D*, shaft *E* of which is geared to the spindle *F* of the governor *G*. Governor *G* operates a lever *H* to actuate a lift device *I* to automatically throw the gripping element 110 into action. As in the first described construction a solenoid 117 is employed, the core 121 of which is adapted to actuate a lever 122, said lever 122 bearing against the arm 114 on the shaft 113 of grip element 110, said arm having a weight 115 as in the first-described construction. When the safety control cable *C* travels beyond a predetermined speed by reason of undue speed of the elevator car, the governor *G* will through the lift member *I* throw the gripping element 110 into action. When the circuit 119 of the solenoid 117 is closed at the pushbutton 20 by a person in or on the car *b*, the lever 122 will be rocked and will rock the arm 114 and throw gripping element 110 into action. The lever 225 is connected with lever 122 by a link 224 and turnbuckle 324 so that the lifting element *I* will also be raised and the gripping element 110 be thrown into action should lever 122 fail from any cause to directly operate said gripping element 110.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. In a safety appliance for elevators, means to grip the safety control cable of the elevator car, automatic governing means to bring said gripping means into action, and manually controlled means carried by and operable from the elevator car to optionally bring said gripping means into action independently of the automatic governing means.

2. A safety appliance for elevators, said appliance comprising gripping means adapted to grip the safety control cable of the elevator, and manually controlled means carried by and operable from the elevator car to optionally bring said gripping means into action for causing a pull to be exerted on said cable and thereby bring the elevator car safety into operation.

3. A safety appliance for elevators, comprising gripping means including a movable gripping element to engage the safety control cable of the elevator car, means to actuate said movable gripping element to move the same into position to grip the safety control cable of the car to bring the elevator car safety into action, and operating means for said actuating means, said operating means being carried by and controllable from the elevator car.

4. A safety appliance for elevators comprising gripping means including a movable gripping element to engage the safety control cable of the elevator car, an element adapted to engage the gripping element to move the same toward gripping position, an electromagnetic device to actuate the second-mentioned element, an electric circuit including said electromagnetic device, and manually operable circuit-closing means in the elevator car, whereby the gripping element may be optionally brought into action by one in or on the elevator car.

5. A safety appliance for elevators comprising an element adapted to be swung into gripping engagement with the safety control cable of the elevator car, a lever adapted to engage said gripping element to move the same toward gripping position, a solenoid, the core of which is adapted to engage said lever and cause the same to move the gripping element, an electric circuit including said solenoid, and manually operable means controllable from the elevator car to close said circuit to energize the solenoid.

6. A safety appliance for elevators comprising an element adapted to be swung into gripping engagement with the safety control cable of the elevator car, a weighted arm on said gripping element; a lever movable into engagement with said arm for throwing the gripping element toward gripping position, means to actuate said lever and manually controlled means carried by and operable from the car of the elevator to cause said actuating means to rock said lever to optionally bring the gripping element into action.

7. A safety means for elevators, comprising a gripping element, automatic speed-controlled means for bringing said gripping element into action, a second gripping element, both of said elements adapted to engage the safety control cable of an elevator

car, operating means for the first-mentioned gripping element, said operating means being independent of said speed controlled means, operating means for the second-mentioned gripping element, optionally operable manually controlled means to actuate said second-mentioned operating means, and means to actuate the first-mentioned operating means by the second-mentioned operating means.

8. A safety appliance for elevators comprising gripping means adapted to grip the safety control cable of the elevator car, and manually controlled means carried by and operable from the car of the elevator to optionally bring said gripping means into action.

DANIEL ARIES MacASKILL.
